(57) **CLAIM**

The ornamental design for a combined digital audio disc player, radio and television tuner and automotive navigation system, as shown and described.

DESCRIPTION

FIG. 1 is a front perspective view of a combined digital audio disc player, radio and television tuner and automotive navigation system showing our new design;

FIG. 2 is a front view thereof;

FIG. 3 is a left side elevational view thereof, the right side elevational view thereof being a mirror image of the left side view;

FIG. 4 is a top plan view thereof;

FIG. 5 is a bottom plan view thereof;

FIG. 6 is a top plan view in open position thereof;

FIG. 7 is a front view in open position thereof; and,

FIG. 8 is a left side view showing the front panel opening half.

The broken lines shown in the drawings form no part of the claimed design.
